UNITED STATES PATENT OFFICE.

CHRISTEN S. CHRISTENSEN, OF CHRISTIANIA, NORWAY.

PUNCH-GAGE.

1,181,737.

Specification of Letters Patent.

Patented May 2, 1916.

Application filed July 15, 1915. Serial No. 40,007.

To all whom it may concern:

Be it known that I, CHRISTEN S. CHRISTENSEN, a subject of the King of Norway, and a resident of Christiania, in the Kingdom of Norway, have invented certain new and useful Improvements in Punch-Gages, of which the following is a specification.

My invention relates to punches for making detents in desired articles, and has particular reference to providing a punch for forming the drill centering holes in metal being formed into a die, and the main object thereof is to provide a gage for the punch which will insure uniformity in the distances of the centering holes from a given line and from each other.

My invention is fully described in the following specification, of which the accompanying drawings form a part, in which like characters refer to like parts in each of the views, and in which:—

Figure 1 is a plan view of a metal plate to be formed into a die, showing my invention and the manner of use thereof; Fig. 2 is a perspective bottom view of the device; Fig. 3 is a bottom plan view thereof; and Fig. 4 is a section taken on the line 4—4 of Fig. 3.

In the drawings forming a part of this application I have shown a block 5 preferably of metal, such as steel or the like, provided with a vertical bore 6 therethrough adjacent one corner thereof and the metal immediately surrounding the same being cylindrically formed, or partially so, as shown at 7, in concentric relationship with the bore 6 and with a wall of uniform and predetermined thickness at the lower edge or end thereof for a reason later pointed out. Adjacent the bore 6 is a similar bore 8 partially through the block 5 from the bottom upwardly and meeting a bore 9 on the axis thereof but of lesser diameter than the bore 8; a pin 10 is snugly and slidably fitted into the bore 8 and provided with an extension 11 of the approximate diameter of the bore 9 and the outer end of which is upset, as shown at 12, to limit downward movement of the pin 10 through the medium of a spring 13 bearing on the inner end thereof.

Loosely and slidably mounted in the bore 6 is a punch 14 of a length exceeding the vertical thickness of the block 5 to permit grasping the upper end thereof by the fingers of the operator to raise the same sufficiently to bury the lower pointed end there-

of within the bore 6; and it will be noted that the spring 13 permits the pin 10 to yield to downward pressure on the block 5 to bury the pin within the bore 8 if the device is resting on a plane surface.

Assuming, by reference to Fig. 1, that a line 15 of a proposed die has been drawn upon a metal plate 16, and it is desired to cut out all of the metal within the boundaries of said line 15, it is the practice to drill a multitude of holes along the inner side of the line 15 and desirably at a uniform distance therefrom and from each other as a preparatory step in the removal of the metal within the confines of said line, and, when the workman guesses at the locations of the centering holes for the drill holes as is often the case, a very ragged and irregular line of centering holes results, or the careful workman may use considerable time in accurately measuring the proposed locations of the drill holes with rule and dividers. It was in order to overcome these unworkmanlike or time consuming methods that my invention was conceived, my tool positively gaging the distance of each drill hole from the line 15 irrespective of its shape and positively gaging the distance between drill holes.

My tool is shown in an initial position in full lines in Fig. 1, and it will be noted that the outer periphery of the cylindrical portion 7 of the block 5 is arranged exactly against the line 15, this being done for each of the drill holes, and thus assuring a uniform distance of the center of each drill hole from the line 15. The wall of the cylindrical portion 7 is of an exterior diameter equaling that of the particular drill to be employed, and the edges of all the drill holes will, therefore, be exactly on the line 15 when completed, the cylindrical and concentric portion 7 permitting the block 5 to be swung through almost an entire circle and still permit the adjustment thereof against the line 15. When the cylindrical portion 7 is against the line 15 and the punch 14 has moved inwardly of the block 5 but is still resting upon the surface of the plate 16, the upper end of the punch may be struck by means of a hammer or other suitable tool, thus producing the centering punch hole for the drill, this being for the initial punch hole let it be assumed. The tool is now moved over the surface of the plate 16 until the pin 10 drops into the

punch hole just made, and the tool is swung with the pin 10 as its center of movement until the cylindrical portion 7 is against the line 15, when the punch may be again struck 5 to produce the second punch hole; the tool is slid over the plate 16 to move the pin 10 in this second punch hole and the block 5 swung as stated to bring the cylindrical portion 7 against the line 15 10 and the punch struck to form the third punch hole, and this may be repeated as often as is necessary according to the length of the line, regardless of its direction to insure uniformity in the positions of the punch 15 holes, and thus of the subsequently drilled holes, with respect to the line 15 and to each other.

My tool may be made in different sizes for different sizes of drills, though it will 20 be understood that the diameter of the outer periphery of the cylindrical portion 7 will, in all cases, equal the diameter of the proposed drill and drill hole.

My invention is very simple, though 25 highly efficient, time-saving, fool-proof, and comparatively inexpensive, and I reserve the right to make any structural changes which do not depart from the spirit of the invention as set forth in the following claims.

Having fully described my invention,

what I claim as new, and desire to secure by Letters Patent, is:—

1. A punch gage, comprising a block provided with a bore at one corner thereof and with a supplemental bore arranged parallel 35 to said first named bore, a punch slideable in said first named bore and projecting beyond the top and bottom of said block, and a yieldingly resisted pin in said supplemental bore projecting from the same side of 40 the block as the sharp end of said punch.

2. A punch gage, comprising a block provided with a bore at one corner thereof and cylindrically formed around the axis of said bore as a center, a punch slideable in said bore and projecting beyond the top and bottom of said block, and a pin in said block in parallel relationship with said punch and projecting from the same side of said block 50 as the sharp end of said punch, said cylindrically formed portion of said block serving as a gage for the axis of said punch to accurately space said axis from a given line.

In testimony whereof I have signed my name to this specification in the presence of 55 two subscribing witnesses.

CHRISTEN S. CHRISTENSEN.
